Edgar T. Teller

ATTORNEY

UNITED STATES PATENT OFFICE.

ROBERT COBURN, OF NEW YORK, N. Y.

HOPPER OR BASIN FOR WATER-CLOSETS, WASHSTANDS, OR URINALS.

SPECIFICATION forming part of Letters Patent No. 556,489, dated March 17, 1896.

Application filed May 27, 1895. Serial No. 550,761. (No model.)

To all whom it may concern:

Be it known that I, ROBERT COBURN, a citizen of the United States, and a resident of New York, county of New York, and State of New 5 York, have invented certain new and useful Improvements in Hoppers or Basins for Water-Closets, Washstands, or Urinals, of which the following is a specification, reference being had to the accompanying drawings, forming a part thereof, in which similar letters of reference indicate corresponding parts.

My invention relates to hoppers or basins for water-closets, urinals and stationary wash-basins such as are usually formed of earthenware, and the object thereof is to provide improved means of supporting and securely fastening the connections with water and waste pipes and protecting, sustaining and strengthening the hoppers, urinals and basins. 15 The invention is fully disclosed in the following specification, of which the accompanying drawings form a part, in which—

Figure 1 is a plan view of a hopper or basin provided with my improvement, with parts being shown in section. Fig. 2 is a side view thereof, and Fig. 3 a side view of another form of basin.

In the practice of my invention I form around the upper rim or edge of the hopper 20 or basin A a rim or flange B, or provide an annular groove C therein, as shown.

Within the groove C or below the flange B is placed a sectional band D, to each end of which is secured or on each end of which is formed a shoulder or projection E, through 35 which pass screw-threaded bolts F, which are passed through and hold in place a plate G, the ends of which are outwardly curved, as shown, to form proper bearings for the head 40 H of the bolts and permit of a proper connection with the shoulders or projections E, with which they are in substantial alignment.

Secured centrally of the plate G and passing therethrough is a short tube K, which communicates with a bore or passage L, formed in the back of the hopper or basin, and by means 45 of which the water-supply pipe is connected with the hopper or basin through the agency of a nut N in the usual manner.

50 A washer or packing O is also employed between the plate G and the body of the hopper, so that the plate may be securely clamped

thereto by the screw-bolts F without danger of breaking the hopper, as will be readily understood.

In Fig. 3 I have shown my improvement applied to a different form of basin, which is held in a vertical position. In this case the band D is formed in two parts, and the separate ends are united at the upper and lower 55 parts in the same manner and by the same means as hereinbefore described, the difference between the two arrangements being that in Fig. 3 the basin is provided with a discharge-pipe P, which passes through the 60 plate G, which holds the bands D together at the lower side of the basin, said pipe P being in communication with a passage formed in the lower side of the basin, (not shown,) but which will be readily understood.

When constructed and applied as shown and described, my invention constitutes a simple and effective device for producing the desired result. There are no spurs or horns projecting from the hopper, urinal or basin 70 therefor. There is no danger of breaking the connections, as in the present system, where, when the spur or horn is broken, the whole 75 fixture is lost, and, furthermore, the necessary plumbing in connection therewith can be done with much greater ease and much less difficulty than formerly.

Having fully described my invention, I claim and desire to secure by Letters Patent—

1. The combination with a hopper or basin for water-closets, urinals and washstands provided with an annular groove around the rim thereof, of a sectional band secured in said groove, the ends of the separate sections of 85 the band being united at the top and bottom of the hopper or basin, by means of clamping-plates connected therewith, and means connected with the upper plate for forming a connection with a water-supply pipe, and with 90 the lower plate for forming a connection with a discharge-pipe, each of said pipes being in communication with the interior of the hopper or basin, substantially as shown and described.

2. The combination with a hopper or basin, of a rim B thereon provided with an annular groove C, a band D arranged in said groove a shoulder E on each end of said band, the

plate G having bearings formed thereon, the bolts F securing said plate and the shoulders together, the head H a short tube K passing through the plate and communicating with a bore L in the hopper or basin, and a washer O arranged between the plate and the hopper or basin, substantially as described.

5 In testimony that I claim the foregoing as

my invention I have signed my name, in presence of the subscribing witnesses, this 25th 10 day of May, 1895.

ROBERT COBURN.

Witnesses:

PERCY I. GRIFFITH,
L. M. MULLER.
